UNITED STATES PATENT OFFICE.

WILLIAM A. KÖNEMAN, OF MILWAUKEE, WISCONSIN.

WASHING APPARATUS FOR RECLAIMED RUBBER.

No. 895,770.

Specification of Letters Patent. Patented Aug. 11, 1908.

Application filed September 19, 1907. Serial No. 393,727.

To all whom it may concern:

Be it known that I, WILLIAM A. KÖNEMAN, a citizen of the United States, residing at Milwaukee, in the county of Milwaukee and State of Wisconsin, have invented a new and useful Improvement in Washing Apparatus for Reclaimed Rubber, of which the following is a specification.

In the art of reclaiming rubber from rubber-waste, involving boiling of the material, in finely-divided condition, in an acid or an alkali solution, or in each solution in succession, the resultant product requires to be thoroughly washed in water to remove all remnant of the chemical adhering to it and cleanse it of the impurities known as "muck" contained in the made-up stock from which the articles forming the waste were produced.

My invention consists in a machine, the construction of which peculiarly adapts it for the washing-purpose referred to.

In the accompanying drawings, Figure 1 shows my improved washing-apparatus by a view in end-elevation; Fig. 2 is a transverse section of the same taken at the line 2 on Fig. 3 and viewed in the direction of the arrow, and Fig. 3 a longitudinal section taken at the line 3 on Fig. 1 and viewed in the direction of the arrow.

In a suitable frame 4 provided with an inclined liquid-shedding table 5 from which a wash-water discharge-conduit 6 leads, as to settling-riffles, tanks or a sewer (not shown), is journaled above the shelf a shaft 7, shown to be of rectangular cross-section between its journaled ends, though it may be of other shape. The shaft passes lengthwise through a receptacle 8 for the material to be washed, this receptacle being hung in the frame to adapt it to be turned, as and for the purpose hereinafter described, from its normal upright position, and consisting of a rounded bottom of perforated sheet-metal forming a screen 10 and a box-like upper portion 11, with closing heads 12, 12, through which the shaft passes. The screen is reinforced by bars or timbers 13 spaced apart and extending between the heads 12. Above the receptacle are supported spraying pipes 14 for supplying the washing-water to the receptacle. On the shaft are secured to extend at right-angles to it and at uniform distances apart sets of wipers, each set consisting of two wipers extending from the shaft in opposite directions, and the sets extending successively at right-angles to each other crosswise of the

shaft. Each wiper consists of arm 16 rigidly bolted to the shaft and terminating in a head 15 secured on the outer end of the arm and in which is clamped a flexible rubber blade 18 to bear against the inner surface of the screen 10 in the rotation of the shaft. The disposition of the wipers is such as to cause the blades 18 of the successive sets to overlap one another.

The shaft 7 is driven through the medium of a gear 19 on one end by a pinion 20 meshing therewith on a power-shaft 21. For turning the receptacle 8 it is provided on each end, about the ends of the head 13, with racks 22 engaged by pinions 23 on the ends of a shaft 24 journaled in the frame of the apparatus and carrying on one end a gear 25 with which meshes a pinion 26 journaled on the frame and provided with a crank-handle 27 for turning it by hand, or with any other suitable means to adapt it to be turned by power.

To operate the apparatus the rubber to be washed is dumped or run into the receptacle, in quantity sufficient to partially fill it, the water is turned on to spray from the pipes 14 into the receptacle, and the shaft 7 is rotated. The particles of the recovered rubber undergoing washing are lifted by the blades of the wipers in rotating the material, subjecting it to a stirring action to continuously present fresh portions of the batch to the spray. The mesh of the screen is much finer than the particles of rubber to prevent passage thereof through it while permitting the washing water containing the impurities (mineral slimes, etc.) to run through it and escape by way of the conduit 6. The flexible blades 18, by rubbing against the inner surface of the screen keep it clear to permit the wash-water to run freely through it, and they push the material ahead of them, squeezing it upon itself, thereby squeezing the chemical muck out of the particles of rubber and facilitating its removal by the action of the water. When the washing operation is completed the water-spray is turned off and the rotation of the shaft 7 arrested. To facilitate removal from the washing-apparatus of the clean rubber, which has to be thoroughly dried preparatory to working it up into stock for the manufacture of rubber goods, the receptacle 8 is adapted to be tipped to a horizontal position by turning the handle 27, whereby rotation of the shaft 24 ensues to engage the pinions 23 and turn the receptacle accordingly on the

shaft 7. The receptacle may, if desired, be completely turned over and the washed material may be readily dumped or shoveled into suitable receptacles, conveyers, or the like, for removal to a drying apparatus, I also employ the apparatus for washing the finely divided material before subjecting it to the chemical-solution treatment referred to.

What I claim as new, and desire to secure by Letters Patent, is—

1. In a rubber-washing apparatus, the combination of a frame, a receptacle for the material to be washed supported on the frame and having a screen-bottom, a rotatory shaft extending through the receptacle, wipers on the shaft having flexible blade-ends extending against the inner surface of the screen, and a solution-receiving device below the screen, for the purpose set forth.
2. In a rubber-washing apparatus, the combination of a frame, a receptacle for the material to be washed supported on the frame and comprising a rounded screen-bottom on a box-like upper portion with end-closing heads, a rotatory shaft extending through said heads, wipers on the shaft having flexible blade-ends extending against the inner surface of the screen, and a solution-receiving device below the screen, for the purpose set forth.
3. In a rubber-washing apparatus, the combination of a frame, a receptacle for the material to be washed supported on the frame and having a screen-bottom, a rotatory shaft extending through the receptacle, wipers on the shaft comprising arms secured on the shaft to radiate therefrom and terminating in heads having fastened upon them flexible blades extending against the inner surface of the screen, and a solution-receiving device below the screen, for the purpose set forth.
4. In a rubber-washing apparatus, the combination of a frame, a receptacle for the material to be washed supported on the frame and comprising a rounded screen-bottom on a box-like upper portion with end-closing heads, a water-spraying pipe above said receptacle, a rotatory shaft extending through said heads, and wipers on the shaft, having flexible blade-ends extending against the inner surface of the screen, for the purpose set forth.
5. In a rubber-washing apparatus, the combination of a frame, a receptacle for the material to be washed rotatably supported on the frame and having a screen-bottom, a rotatory shaft extending through the recep-

tacle, wipers on the shaft having flexible blade-ends extending against the inner surface of the screen, and a solution-receiving device below the screen, for the purpose set forth.

6. In a rubber-washing apparatus, the combination of a frame provided with a liquid-shedding table, a receptacle for the material to be washed supported on the frame and comprising a rounded screen-bottom on a box-like upper portion with end-closing heads, a rotatory shaft extending through said heads, wipers comprising arms extending at intervals from the shaft toward the sides of the receptacle and terminating in flexible blade-ends adapted to bear against the inner surface of the screen, and a solution-receiving device below the screen, for the purpose set forth.

7. In a rubber-washing apparatus, the combination of a frame, a receptacle for the material to be washed rotatably supported on the frame and comprising a rounded screen-bottom on a box-like upper portion with end-closing heads and screen-reinforcing bars extending, spaced apart, between said heads, gears on the ends of said receptacle, a shaft journaled in the frame, provided with means for turning it and carrying pinions meshing with said gears, a rotatory shaft extending through said heads, wipers on said rotatory shaft, having flexible blade-ends extending against the inner surface of the screen, and a solution-receiving device below the screen, for the purpose set forth.

8. A rubber-washing apparatus comprising, in combination, a frame provided with a water-shedding table, a receptacle for the material to be washed rotatably supported on the frame and having a rounded screen-bottom on a box-like upper portion with end-closing heads, means for turning said receptacle, a water-spraying pipe supported to discharge downwardly into the receptacle through said upper portion, a shaft journaled in the frame and extending through said heads, and sets of wipers composed of arms secured to the shaft to extend at intervals along the same and at substantially right-angles thereto and terminating in heads carrying flexible blades adapted to bear against the inner surface of the screen, for the purpose set forth.

WILLIAM A. KÖNEMAN.
